UNITED STATES PATENT OFFICE.

WYLIE KEIFFER, OF PERHAM, MINNESOTA.

ATTACHMENT FOR POTATO-DIGGING MACHINES.

Application filed May 25, 1922. Serial No. 563,609.

To all whom it may concern:

Be it known that I, WYLIE KEIFFER, a citizen of the United States, residing at Perham, in the county of Otter Tail and State 5 of Minnesota, have invented certain new and useful Improvements in an Attachment for Potato-Digging Machines; and I do hereby declare the following to be a full, clear, and exact description of the invention, such as 10 will enable others skilled in the art to which it appertains to make and use the same.

This invention relates to a collecting or gathering attachment for potato digging machines.

15 It is aimed to provide an attachment which may be connected to various types, sizes and styles of potato digging machines and in which the fall of the potatoes will be slight so as to avoid bruising them, and by 20 means of which hand picking of potatoes is avoided in that it will deposit the collected or gathered potatoes in piles and in which the hand picking of rows subsequent to digging is avoided and which is a tedious and 25 expensive practice although indulged in generally at the present time.

Another object is to provide a construction in which the gathering attachment may be dumped or lowered, either automatically 30 or by manually operated means, at desired intervals.

Additional objects and advantages will become apparent from a consideration of the 35 description following taken in connection with accompanying drawings illustrating one practical embodiment.

In said drawings:—

Figure 1 is a plan view illustrating the 40 attachment applied to a potato digging machine, the latter being shown fragmentarily,

Figure 2 is a side elevation of the parts of Figure 1,

Figure 3 is a rear elevation;

45 Figure 4 is a detail perspective view illustrating the adjustable attaching means for the attachment; and

Figure 5 is a detail perspective view illustrating means for permitting automatic dumping of collected potatoes of a predetermined weight.

Like reference characters designate like or similar parts in the different views.

In said drawings, a potato digger has been 50 generally shown as at A, to illustrate the use and attachment of my improvement. This digger being conventional, it is sufficient to

say that the potatoes follow a course in the direction of and discharge from a table represented by spaced rods or fingers B. The frame of the digger A is designated C, particularly having sides at D.

The attachment includes a mounting rod or bar 10 which is pivotally journaled in attaching brackets generally designated 11. These brackets may be of any suitable construction and for instance of three parts 12, 13 and 14 those at 12 and 13 having arcuate portions 15 embracing the rod 10 secured in such relation by means of one or more adjustable bolts at 16. This construction enables the brackets 11 to be placed at any desired location along the bar 10 and to thereby adapt the attachment for connection to various types and sizes of digging machines. The parts 14 may be bolted to the parts 12 75 at 17 to engage the sides D of the digger A.

Said bar 10 forms part of a gathering or collecting element or basket 19, generally of reticulate form and dished as shown, being completed for example by curved bars 20 80 disposed on top of said bar 10 and joined and riveted or otherwise fastened to a reinforcing and supporting bar 21 disposed below the same, whereby the upper surface of the basket will be smooth and the potatoes 85 will not be bruised by contact therewith.

The basket is disposed directly below and relatively close to the fingers B so that potatoes in traveling over the fingers B will not have to drop a material distance and 90 whereby they will be saved from bruising. In actual practice, the drop from the fingers to the basket will not be more than one or two inches. The basket is normally disposed horizontally so that the potatoes may readily 95 fall thereinto from said fingers B.

The tendency of the basket 19 is to fall to the ground under weight of the potatoes therein in order to discharge them. Said basket is held in a horizontal position 100 counter to the weight of the potatoes in any suitable manner, preferably by trip or actuating means. This means may consist of a post or rod 22 rising from the basket and having a link or rod 23 pivoted thereto and 105 extending forwardly therefrom preferably to a point adjacent the operator's seat on the potato digging machine. At its front end, said rod 23 is pivoted at 24 to a lever 25 pivoted at 26 and adapted to be maintained in its adjusted position through the medium of a suitable plunger thereon.

- adapted to coact with a gear segment or rack 26'. When the lever 25 is in its foremost position, the basket 19 is elevated. The lever 25, may be thrust rearward which through the medium of the link 23 and rod 22 will lower the basket 19 into contact with or adjacent to the ground so that the potatoes will fall therefrom onto the ground into a pile.
- 10 It will be seen that as the potato digger operates, the potatoes will pass over the rods or fingers B and fall into the basket 19, being gathered or collected therein, and that the same may be emptied or dumped at desired intervals through the manipulation of the lever 25.

Particular attention is called to the fact that this device saves considerable labor, avoiding "row picking" as is done by hand 20 at the present time in order to arrange the potatoes in piles, which my improvement does as a continuation of the digging operation. Also particular attention is called to the slight drop of the potatoes from the 25 fingers into the basket which avoids injury thereto.

In some instances, the basket 19 may be arranged to automatically discharge under the collection of potatoes of predetermined weight as suggested in Figure 5. In the 30 form of that figure, the construction is the same as in the other form except that the arm 22, link 23, and lever 25 are dispensed with. In their stead, an arm or rod 27 is provided which is pivoted as at 28 to the basket. The rod 27 is slidably mounted through an elongated slot 29 in a guide bar 30 which may be secured as by bolts at 31 to one of the sides D of the digger A. 40 Above the bar 30, a coil spring 32 surrounds the same and rests on the bar. A nut or other fastening means 33 may be provided at the upper end of the rod 27 to form an abutment for engagement by the spring 32. 45 As the spring 32 is of a known tension, the basket 19 will automatically tilt or swing downwardly from its pivot at the bar 10 upon potatoes of a predetermined weight being collected on the basket 19. It will be 50 understood that the spring 32 is readily

removable through removal of the nut 33, in order that others of varying tension may be substituted therefor and thus in conformance with the weight under which the basket 19 is adapted to empty or unload. After 55 the basket 19 has unloaded, the spring 32 will restore the basket 19 to a normal or receiving position.

As will be obvious the rod 27, bar 30 and spring 32 and associated parts may be duplicated on the other side of the digger.

As merely practical embodiments have been shown by way of example, it is to be understood that changes in the details may be resorted to provided they fall within the 65 spirit and scope of the invention.

I claim as my invention:—

1. A machine of the class described having a basket to receive products, said basket having an attaching bar, and attaching 70 means adjustable along said bar and for engagement with the machine.

2. A machine of the class described having a reticulate basket to receive products, an attaching bar, clamps adjustable along 75 said bar and attachable to the machine, said bar being pivoted to said clamps, and said basket being movable from a normal to a dumping position.

3. A machine of the class described having a discharge table, a reticulate basket under and relatively close to said table substantially avoiding falling of the products into the basket, said basket having an attaching bar, longitudinal bars on said attaching bar, a brace bar for said longitudinal bars, said attaching bar and brace bar being lowermost whereby the upper surface of the bars will be substantially uninterrupted to avoid bruising of products, brackets attachable to the machine, and said brackets having separable parts to permit adjustment along said attaching bar and to pivotally mount said attaching bar.

In testimony whereof I affix my signature 85 in presence of two witnesses.

WYLIE KEIFFER.
